UNITED STATES PATENT OFFICE.

JOSEPH R. FRANCE, OF NEWARK, NEW JERSEY.

CELLONITE OR NITRO-CELLULOSE ARTICLE.

SPECIFICATION forming part of Letters Patent No. 328,848, dated October 20, 1885.

Application filed July 28, 1885. Serial No. 172,890. (No model.)

To all whom it may concern:

Be it known that I, JOSEPH R. FRANCE, a citizen of the United States, residing at Newark, in the county of Essex and State of New Jersey, have invented new and useful Improvements in Cellonite or Nitro-Cellulose Articles, of which the following is a specification.

It has long been known that nitro-cellulose compounds, under various names—such as parkesine, partsine, cellonite, celluloid, zylonite, pyroxylene, &c.—have been used in various arts for ornamental or useful purposes, or for both combined. In all such uses, with the exception of artificial palates and similar uses, when only a thin sheet molded into proper form was to be used, the nitro-cellulose compound was applied and utilized as a coating or covering simply for some body forming the base and having the contour of the finished article. Hitherto such bases have always been of material subject to change with varying thermal or hygrometric variations. For instance, wooden cores or bosses have been used in very many articles, the ornamental and preservative finish therefor being given by a coating of a nitro-cellulose compound. In such cases the wooden core, no matter, apparently, how thoroughly seasoned, would still shrink, loosening the coating therefrom or causing such coating to crack and open in seams, this being due to the fact that wood is always subject to and acted upon by hygrometric changes. In other cases metallic cores or bases have been used, finished, ornamented, or protected by a nitro-cellulose covering. Such metallic cores are always subject to molecular changes, to change of size and contour by thermal variations, tending at one time to expand and crack or seam the coating, at another to shrink therefrom. These defects are especially objectionable in view of the tendency of the material itself—the nitro-cellulose composition—to warp when in use. This warping tendency renders the compound difficult to satisfactorily work, and for the articles, as hitherto made, to retain the originally given and desired shapes. If, then, in view of these facts, a wooden core, or core of any other material affected by hygrometric changes, apt to shrink or swell as the atmosphere is damper or dryer, or a core affected

by thermal changes, as a metal core, expanding or contracting with variations of temperature, is used, the changes in such core give full play, afford ample opportunity for the warping tendency of the nitro-cellulose covering to be exercised, with the result that such covering is finally loosened from the core or is cracked and seamed thereupon.

In view of these facts, therefore, my invention consists in an article having a protective or ornamental covering of a nitro-cellulose compound upon a base, or upon a base composed largely and for the most part of some material not susceptible in any appreciable degree to ordinary thermal or hygrometric changes, a base which is non-shrinkable for covering or coating with the nitro-cellulose compound. For this purpose I have found shellac and equivalent gums a very suitable material. Shellac, though capable of liquefaction, and in such state of being cast or molded into any desired shape, is non-shrinkable. At the same time it is not influenced by any thermal and hygrometric changes within the ordinary limits of such changes.

In carrying my invention into effect, therefore, I make a base of any suitable or desired form for the use to which the finished article is to be applied, of shellac or similar gum or substance having similar qualities, and then apply thereto a coating of a nitro-cellulose compound, colored or ornamented as taste may dictate. This coating may be made in tubes, which, after being softened by heat and pulled upon the core or base, is placed in proper dies, which flows the cellonite around the core, closing up all end openings. It may also be made in the form of sheets applied thereto, the seams and openings being then closed and smoothed by proper dies, or in any other practicable method; or, again, this finishing coating of the nitro-cellulose composition may be made by deposition by the insertion of the base in a solution of the nitro-cellulose composition until the proper or desired thickness has been deposited thereon and the solvent allowed to evaporate, leaving a hard-finished coating or skin of the compound upon the article.

If the article is to possess greater tensile

strength than would be conferred by such base, as in the case of sword-grips, knife and fork handles, whip-handles, rings, &c., a stiffening-piece of metal, as a wire or thin strip, may be placed therein, it being so protected by this base that it is not readily affected by ordinary thermal or hygrometric changes.

The invention thus set forth is typified in a few of the uses to which it is applicable in the drawings, wherein Figures 1 to 6 represent, in Fig. 1 in perspective, and the remainder in section, its application to such uses. It is of course understood that its uses are not confined to the example here given, but may be almost indefinitely extended; that these examples or illustrations are merely typical, and given with the object of rendering the invention more readily and clearly understood.

In Fig. 1 is represented the grip of a sword, the reference-numeral 2 indicating a base or body of shellac or material having similar properties, which is to be passed around or fitted upon the tang of the blade within the guard, such tang fitting in the longitudinal aperture 1. Upon the body or base is made the coating 3, of nitro-cellulose compound, colored and ornamented as desired.

In Fig. 2 is shown a knife or fork handle, such body or base here designated, 5, being pressed, formed, or fastened upon the tang 4, and covered with the nitro-cellulose coating, covering, or skin 6.

In Fig. 3 are shown the parts of a pistol or gun grip or stock, 7 and 9 being the bodies or bases formed as explained and covered with nitro-cellulose 8 and 10, the usual screws, 11, for fastening them to the iron or metal framework, passing therethrough.

In Fig. 4 is shown a truss-pad, in which for increased rigidity and bearing force, a small or thin metal plate, 13, may be used, upon which is fastened, formed, or cast a body, 12, of appropriate shape and contour, over which is the coating 14 of nitro-cellulose.

In Fig. 5 is shown a ring for use in harness or any other connections in which such rings may be desirable. It is composed, primarily, of a body or base, 17, as described, with a coating or skin, 18, of nitro-cellulose. If desired for increased strength, a wire or strip, 19, of metal, whalebone, or other suitable material may be embedded within the base or body 17.

In Fig. 6 is shown a part of a whip, cane, or umbrella-stock, 22 being the base or body thereof with the nitro-cellulose coating 23, the end or handle thereof being finished in any suitable or desired design or configuration. In such cases also, for increased strength and rig-

idity, a wire, rod, or strip, 24, of any suitable material, may be embedded in the body or base. It will be noted that such wire, rod, or strip is in Fig. 1 the tang of the blade, extending between the ends of the guard; in Fig. 2 it is the tang 4; in Fig. 4 it is the plate, while in Figs. 5 and 6 the wire, rod, or strip is 19 or 24. In all these cases the amount of the wire, rod, or strip, whether of metal, rattan, wood, or whalebone, or other material, is of exceedingly small bulk relatively to the case or body, and is so covered, secured, and protected therein as not to be subject to ordinary variations in thermal and hygrometric conditions.

The coverings or coatings of nitro-cellulose material may, as before explained, be applied in any of the well-known ways—for instance, as a tube softened by heat, applied upon the bodies 2 5 &c., the open end or ends being closed and smoothed by suitable rollers or dies, or by sheets of the coating placed therearound, and the seams and openings closed and finished by dies or rollers; or it may be applied by deposition by dipping the base in a solution of the nitro-cellulose material.

Thus made an article is produced in which the interior body or base is of cheap yet sufficiently strong material, not affected by such thermal and hygrometric changes as it is likely to be subjected to, while the body or base not being subjected to such changes, the danger of the coating, warping, or cracking is obviated.

Having thus described my invention, what I claim is—

1. As a new article of manufacture, an article having a base or body of a non-shrinkable material not affected by ordinary thermal or hygrometric changes and a coating of nitro-cellulose compound, substantially as described.

2. The combination of a core, base, or body made of a shellac or equivalent composition and a coating of a plastic material, such as a nitro-cellulose compound, substantially as described.

3. The combination of a core, base, or body made of a shellac or equivalent composition, a stiffening or fastening strip, rod, or wire, and a coating of a plastic material, such as a nitro-cellulose compound, substantially as described.

In testimony whereof I affix my signature in presence of two witnesses.

JOSEPH R. FRANCE.
